UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,819, dated October 29, 1895.

Application filed September 27, 1895. Serial No. 563,933. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of a series of wreaths of leaves arranged in a vertical line and connected by vertical sprays of leaves with ornamental stripes or bands arranged vertically on each side of said wreaths and a continuous spray or line of leaves at each side of said ornamental stripes or bands, as represented in the accompanying drawing.

The border of said design consists of a series of interlacing wreaths of leaves with festoons of ribbon interlacing with the wreaths, 20 as shown in the drawing. A wide horizontal band forms the bottom of the border.

What I claim is—

1. The design for wall paper herein shown and described.
2. In the design for wall paper, the border herein shown and described.

Witness my hand this 24th day of September, 1895.

CHARLES BOOZ.
